UNITED STATES PATENT OFFICE.

SIGMUND GOLOMBEK, OF NEW YORK, N. Y.

DISPLAY-HOLDER FOR WINDOWS.

No. 840,618.

Specification of Letters Patent.

Patented Jan. 8, 1907.

Application filed September 6, 1906. Serial No. 333,561.

To all whom it may concern:

Be it known that I, SIGMUND GOLOMBEK, a citizen of Russia, residing at New York city, Manhattan, county and State of New York, have invented new and useful Improvements in Display-Holders for Windows, of which the following is a specification.

This invention relates to a holder adapted to be directly secured to the glass of a show-window and to display watches, cards, and other articles from said window.

In the accompanying drawings, Figure 1 is a front view of my improved display-holder; Fig. 2, a rear view; Fig. 3, a left-hand end view, and Fig. 4 a right-hand end view thereof.

A rubber suction-cup 5 has an integral outwardly-projecting stud 6. This stud carries a wire clasp wound upon the same, as at 7. The rear shank of the wire extends from coil 20 7 first down, as at 8, then into a circle, as at 9, then down diametrically across said circle, as at 10, and then up again, as at 11. The circular part 9 of said wire constitutes the fixed jaw of a clasp, while the parts 10 11 collectively constitute a hook in front of said jaw.

The front shank of the wire is inclined from coil 7 forwardly, as at 12, and then back horizontally, as at 13, to pass the straight part 8 of the rear shank. It is then bent into 30 a circle 14 back of circle 9. This circle 14 constitutes the movable jaw of the clasp, while the parts 12 13 collectively constitute a finger-piece for operating said jaw.

In use the device is attached to any part of

a window 15 by pressing the cup 5 tightly against the same, so that the cup will be held to the glass by suction. By a pressure upon the finger-piece 12 13 the jaw 14 will be opened and permit the introduction of a price-card into the clasp, while a watch or similar light article may be suspended in front of said card from hook 10 11. In this way means are provided for securing to a window various light articles, together with their price-cards, without damaging the glass and in such a manner that the arrangement of the holders and of the goods displayed from the same may be readily varied.

What I claim is—

1. In a display-holder for windows, a suction-cup having a stud, combined with a wire engaging said stud and having a pair of jaws, and a hook in front of said jaws, substantially as specified.

2. In a display-holder for windows, a suction-cup having a stud, combined with a wire engaging the same and having a front shank bent to form a fixed jaw and a hook, and a rear shank bent to form a finger-piece, and a movable jaw back of the fixed jaw, substantially as specified.

Signed by me at New York city, Manhattan, New York, this 5th day of September, 1906.

SIGMUND GOLOMBEK.
